UNITED STATES PATENT OFFICE.

HENRY CHERRY AND THOMAS CHERRY, OF BROOKLYN, NEW YORK.

COMBINATION TOOL.

Application filed April 9, 1925. Serial No. 21,964.

The present invention relates to a combination tool; and has for its principal object to combine in a single structure, the features of a hammer, nail-puller, and ice-
5 pick.

Another important object of the invention is to combine these features in a comparatively compact and convenient arrangement, in order that each feature may be used
10 separately and independently to advantage.

A still further object of the invention is to provide a combination tool of this nature, which is exceedingly simple in construction, one which is efficient and reliable in use, inexpensive to manufacture, strong, durable, easy to manipulate, and otherwise well adapted to the purpose for
15 which it is designed.

With the above and numerous other objects in view, as will appear as the description proceeds, the invention resides in certain novel features of construction, and in the combination and arrangement of parts as will be hereinafter more fully described and
20 claimed.

In the drawing:

The figure is a fragmentary elevation of the tool.

Referring to the drawing in detail, it will
30 be seen that 5 designates an elongated handle having the head 6 formed integrally or otherwise on one end thereof and provided with the hammer 7 and claw nail puller 8, the nail puller and hammer proper being

oppositely disposed as in an ordinary claw hammer.

The handle 5 is provided with a longitudinally extending groove 11. An ice pick 12 is pivoted in the end of the groove 11 adjacent the head 6. An extension 14 is disposed laterally from the ice pick 12 for engaging in a notch 18 provided in the hammer 7. The extension 14 is formed of spring metal and has its curved extremity 19 adapted to be sprung in and out of the diagonally disposed notch 18 as the pick is swung toward or away from the hammer 7. When not in use the pick 12 may be swung to be disposed in the groove 11.

Having thus described our invention, what we claim as new is:

A tool of the class described including an elongated handle having a longitudinally extending groove therein an ice-pick pivoted in one end of the groove so that it may be 55 swung to extend into the groove or to a position angularly of the handle, a head formed on the handle adjacent the pivot of the ice-pick, an extension on the head, said extension provided with a diagonally extending notch, and a resilient arm extending from the ice-pick and having a curved terminal adapted to swing into and out of the notch.

In testimony whereof we affix our signatures.

HENRY CHERRY.
THOMAS CHERRY.
